Primary Examiner — Susan Bennett Hattan*Assistant Examiner* — Brett Miller(74) *Attorney, Agent, or Firm* — Roylance, Abrams, Berdo & Goodman, L.L.P.(57) **CLAIM**

The ornamental design for a liquid container, as shown and described.

DESCRIPTION

FIG. 1 is a front elevation view of a liquid container showing my new design.

FIG. 2 is a plan view thereof.

FIG. 3 is a bottom view thereof.

FIG. 4 is a left side elevation view thereof.

FIG. 5 is a right side elevation view thereof.

FIG. 6 is a front elevation view thereof showing cap element is opened.

FIG. 7 is a plain view thereof showing cap element is opened.

FIG. 8 is a left side view thereof showing cap element is opened.

FIG. 9 is a right side view thereof showing cap element is opened.

FIG. 10 is an enlarged detail view according to detail 10 in FIG. 7; and,

FIG. 11 is a front elevation view thereof showing the band element removed.

The dash dot lines represent the boundaries of details and form no part of the claimed design.
